UNITED STATES PATENT OFFICE

JULIUS ROEDER AND WILHELM WELLMANN, OF WITTEN, GERMANY

ROLLING MILL AND PROCESS FOR ROLLING TUBES

Application filed June 1, 1928, Serial No. 282,201, and in Germany August 20, 1927.

Our invention relates to rolling mills and methods used in rolling tubes, especially tubes of the smaller diameters. More specifically, this invention relates to a further development of the method described in Patent No. 1,626,481, granted to us April 26th, 1927.

Among the objects of the invention may be mentioned reducing to a minimum the number of passes required at the finishing rolls where tubes of small diameter and small wall thickness are rolled, increasing the production of finished tubes, and making possible the economical production of tubes of the smaller sizes.

With a view to accomplishing these objects, we have combined certain well-known types of mills, examples of such combinations being illustrated in the accompanying drawings, wherein—

Figure 1 is a diagrammatic layout of a mill constructed in accordance with the invention, and

Fig. 2 is a diagrammatic layout of another form of mill which is also constructed in accordance with the invention.

Methods heretofore in use for producing small tubes, from about $2\frac{1}{2}$ " external diameter to the smaller sizes, have consisted in first producing by means of a so-called Swedish rolling mill, or the like, a tube whose wall thickness does not exceed a predetermined dimension depending upon the desired size and wall thickness of the finished tube. The preliminary tube thus produced is then reheated, and is brought to the desired finished dimensions by means of a succession of reducing mills. It has not been possible for the rolling mills heretofore employed to roll down the wall thickness of the pierced round sufficiently to make the smallest sizes of tubes: that is to say, finished tubes such as $\frac{3}{8}$ " gas pipe with a wall thickness of approximately $\frac{1}{8}$ ". Furthermore, in the tube mills heretofore employed, the individual mills are not joined directly to the installations producing the pierced round, because the temperature of the pierced round after its formation is not sufficient under present practice to permit a further reduction of size

without reheating. It has, therefore, been customary to use the very expensive cold drawing process for reducing the wall thickness. After cold drawing it has also been customary to reheat the tube and then to reduce it to the desired finished dimensions. The cold drawing and reheating processes increase the production costs of small diameter pipes (gas pipes for example) and the process cannot result in a low-price commercial commodity.

A further disadvantage, which has seriously limited production, has been the necessity for resetting the rolls employed in existing continuous rolling mills where many successive stand of rolls are employed. Such rearrangement, and the accurate determination of the roll setting, requires considerable time and causes lengthy breaks in operation. It is, therefore, exceedingly expensive.

Previous arrangements have not permitted the production of two or more sizes of tubes on a single sequence of reducing trains at the same time, or with a single roll setting. On the contrary it is now necessary to roll the different tube sizes in separate operations: that is to say, having reduced a certain quantity of one tube size, it is then necessary to reset the rolls before another size can be rolled. Thus if it is desired to reduce several sizes of tubes, without changing the roll setting, it is necessary, according to present practice, to have several reducing trains each with its separate reheat furnace. Thus each reduction is preceded by a reheat operation, or, in the case of the smaller diameters of tubes, by a cold drawing operation and also by a reheating. This requires very extensive and expensive plants, and results in high operating costs and makes the cost of producing the tubes very high. This is precisely what the product here considered cannot bear.

Patent No. 1,626,481, describes a method by which thin walled tubes may be rolled in a few passes without a considerable cooling of the tube, simply by reason of the rapid operation of the few passes required. We have discovered that the heat remaining in the tube after rolling as described in the afore-

said patent is quite sufficient for the tube to undergo an extensive further reduction.

According to the present invention the limitations inherent in present practice are overcome by arranging several reducing trains at intervals in line behind the finishing mill employed according to the aforesaid Patent No. 1,626,481, so that tubes rolled on the latter will pass these reducing trains without reheating and be reduced from the largest to the smallest desired diameters without resetting the rolls or inserting different sizes of rolls. The wall thickness is, of course, controlled by the finishing mill, which is here illustrated as a Swedish rolling mill. The arrangement of mills is such that after passing through any one of the reducing mills the tube can be removed at that point. It is, therefore, possible to secure different degrees of reduction of the pierced round according as the same is allowed to traverse one, a selected number, or all of the mills. The number of possible reductions in any mill train will, therefore, correspond with the number of reducing mills in the train.

In Figure 1 there are illustrated finishing mills *a a* and conveyor *c* upon which the heated tubes may be placed after leaving the finishing mill and when ready for the reducing operation. A series of reducing trains *b*, *b*¹, *b*², *b*³, *b*⁴, *b*⁵, are shown spaced at intervals. Conveyors *c*, *c*¹, *c*², *c*³, *c*⁴, *c*⁵ and *c*⁶, are disposed between the mills *a a* and the respective reducing trains and serve to convey the tubes from the finishing mills *a a* to the first reducing train *b* and from one reducing train to the next. Cooling benches *d*, *d*¹, *d*², *d*³, *d*⁴ and *d*⁵, are placed adjacent to the conveyors *c*¹, *c*², *c*³, *c*⁴, *c*⁵ and *c*⁶, respectively.

The smallest size of pipe which can be economically rolled over a mandrel is about 2 1/2 to 2 3/4" in diameter. The present arrangement will therefore be applicable only for the smaller tube sizes. For example tubes such as gas pipes of diameters between 1 1/2 and 3/8" may be considered. In this case the roll trains are so related that the tube is first rolled to a diameter of 2 1/2" and is then placed upon the conveyor *c*. In passing through the train *b* it is reduced to 1 1/2" external diameter; without appreciable increase in the wall thickness given it by the finishing rolls. If a smaller diameter is desired, the tube coming from the reducing train *b* is allowed to run through the reducing train *b*¹ and is there reduced to 1 1/4" external diameter. By passing the tube coming from the reducing train *b*¹ through the reducing train *b*² a 1" tube is obtained. The reducing train *b*³ will produce a 3/4" tube, the train *b*⁴ a 1/2" tube and the train *b*⁵ a 3/8" tube. The arrangement is such, however, that the tube may be removed after it has

been reduced to any of these diameters which is desired and before entering the next roll train. To accomplish this the tube is merely removed sidewise from the conveyor over which it is traveling (as *c*³) to the adjacent cooling bench (as *d*²).

It is clear from the example, which has just been given, that the present arrangement makes it possible to roll several sizes of pipe (in this case six different external diameters) without making any special adjustment of the reducing rolls, or specially resetting any of the reducing trains. It will also be obvious that this arrangement may be set for larger dimensions as for instance 3", 2 3/4", 2 1/2", 2 1/4", 2" and 1 3/4". It is also evident that tubes for other purposes than for use as gas pipes may be rolled according to this method. Finally it will be seen that a larger or smaller number of reducing trains than that given in the example may be employed.

We may also employ the above principle in this application to the first rolls of a series of reducing mills, and alter or reset as desired the final train in order to give different dimensions of produce. Such an installation proves exceedingly useful where length of valuable floor space is not adequate for the installation of a sufficient number of roll trains to operate as above described in producing a sufficient variety of tube diameters.

Figure 2 illustrates an example of such a combination. Four reducing trains *b*, *b*¹, *b*², and *b*³, are shown aligned behind each other. The operation of the first three trains may be exactly like that described in the above discussion of Figure 1. That is to say, a first reduction to 1 1/2" diameter, a second reduction to 1 1/4" diameter and a third reduction to 1" diameter. In the present case the reducing trains *b*, *b*¹, and *b*² are not altered. However, the reducing train *b*³ may be so constructed that it may be set for rolling a 3/4" tube or if desired a 1/2" or a 3/8" tube instead.

It will be clear from the foregoing description of the form illustrated in Fig. 2 that such an arrangement will permit the rolling to four tube sizes at any time without making changes in the roll set up. To produce a fifth or a sixth size it is only necessary to reset the rolls of one roll train.

We claim:

1. A tube rolling mill for producing small diameter tubes from tubes of predetermined wall thickness coming hot from a Swedish rolling mill, comprising a plurality of reducing trains arranged in series one behind the other, conveyors between the reducing trains and cooling benches adapted to receive the tube from a conveyor after passing any one of the reducing trains, fixed rolls in said reducing trains preceding the final train to provide a fixed size of pass, and adjustable

- rolls in said final train to provide a pass of
adjustable sizes.
- 5 2. A process for producing small diameter
tubes comprising rolling a tube to a prede-
termined diameter and wall thickness on a
Swedish rolling mill over a mandrel, taking
the hot tube from the Swedish rolling mill,
and rolling it through a plurality of reduc-
ing mill trains arranged in series.
- 10 3. A process for producing small diameter
tubes comprising rolling a tube to a prede-
termined diameter and wall thickness on a
Swedish rolling mill over a mandrel, taking
the hot tube from the Swedish rolling mill,
15 and rolling it without reheating through a
selected number of reducing mill trains ar-
ranged in series to effect the desired degree
of reduction.

- 20 4. A process for producing small diameter
tubes comprising rolling a tube to a prede-
termined diameter and wall thickness, on a
Swedish rolling mill over a mandrel, taking
the hot tube from the Swedish rolling mill,
rolling it, without reheating, through a plu-
25 rality of reducing mill trains arranged in
series, and varying the setting of the last
train in the series to effect the desired degree
of reduction.

In testimony whereof we have signed our
25 names to this specification.

JULIUS ROEDER.

WILHELM WELLMANN.
